SPOUT AND CAP

Carl McQuinn, Decatur, Ill., assignor to Williams Sealing Corporation, Decatur, Ill., a corporation of Illinois

Application March 22, 1937, Serial No. 132,436

8 Claims. (Cl. 221—3)

The present invention is a dispensing container spout and a closure for the same.

An object of the invention is the provision of a container spout having a substantially dripless pouring lip and a closure engageable over the spout and lip and capable of effecting a sealing of the contents of the container.

Another object of the invention is to provide a pouring spout which will afford a uniform engagement circumferentially of the spout with a closure of the type having a contractile skirt. Such a closure is shown, for example, in Patents 1,743,945, granted January 14, 1930, and 1,214,734, granted February 6, 1917.

A further object of the invention is to provide the combination of a pouring spout and a closure of the character above described in which a positive locking engagement of the cap and the spout and an effective seal between the cap and the spout are uniformly provided circumferentially of the spout and cap.

In the production of a spout having a pouring lip, it is desirable that the lip be so formed as to insure the free pouring of the contents of the container with a minimum of dripping, and at the same time cooperate with a closure to insure an effective seal. The prior art discloses spout constructions which have pouring lips and depending flanges surrounding the spouts and lips and provided with closure engaging means. These flanges are usually interrupted, such as being cut away or depressed at the pouring lip to insure a minimum of dripping after the pouring operation. I have found, however, that this advantage is nullified by decreasing the efficiency of the sealing action. That is, the cutting away or depressing of the spout flange at the pouring lip causes leakage and does not provide the effective seal that is obtained by the use of an unbroken uniform skirt or flange. The present invention is designed to obviate these objectionable features by providing a spout construction wherein the pouring lip is dripless and at the same time insures an effective seal between the spout and closure. This is accomplished by forming the spout with a pouring lip and a depending flange surrounding the spout and lip and terminating in a uniform edge spaced from the wall of the spout. With this construction, I combine a cap having a top sealing surface and a depending contractile skirt adapted to extend below the edge of the spout flange whereby contraction of the skirt will draw the latter inwardly and downwardly into engagement uniformly with the entire flange of the spout, and thus produce

an effective sealing action between the top of the cap and spout.

Another object is the provision of a cap having a contractile skirt, a split ring mounted in the skirt and a sheet metal lever for contracting the ring and skirt.

With the foregoing and other objects in view, the invention will now be more particularly described, reference being had to the accompanying drawings in which:

Figure 1 is a side elevation of one embodiment of the invention showing the cap applied to the spout.

Figure 2 is an end elevation of the spout and cap shown in Figure 1.

Figure 3 is a top plan view thereof.

Figure 4 is a transverse vertical section through the cap and spout.

Figure 5 is a longitudinal vertical section through the cap and spout.

Figure 6 is a plan view of the spout with the cap removed.

Figure 7 is a longitudinal vertical section through the spout with the cap removed.

Figure 8 is a modification of the cap shown in Figure 1.

Figure 9 is a detail view of the cap lever.

Figure 10 is a section on line 10, 10 of Figure 9.

Figure 11 is a section on line 11, 11 of Figure 9.

Figures 12 and 13 are details of one method of forming the apertures in the lever, and

Figures 14 to 22a inclusive, illustrate successive steps in the formation of the pouring spout.

Referring now to the drawings, the numeral 35 10 designates generally a sheet metal container having a spout 11 of substantially circular formation projecting upwardly therefrom. This spout is provided with a pouring lip 12 which extends outwardly past the circular contour of the spout.

40 The extreme top portion of the spout is beaded or rounded to form a sealing surface 13 which entirely surrounds the spout and pouring lip and, as clearly shown in Figure 6, has a substantially oval contour. The spout is provided with a relatively narrow depending flange 14 forming a continuation of the sealing surface 13. This flange is unbroken and substantially uniform in construction and it is not interrupted, depressed or cut away at any point throughout its contour.

45 By providing a circumferentially continuous spout flange, there is assured a uniform gripping of the spout by the contractile skirt of the closure, and consequently a uniform seal circumferentially of the pouring lip. Preferably, the flange is of uniform width circumferentially

of the spout, thereby assuring a uniform seal around the pouring lip, and terminates short of the lower edge of the closure skirt whereby the contracted edge of the closure skirt may be drawn beneath the free edge of the spout flange. Further, the substantially sharp edge 15 cooperates with the pouring lip 12 to form an efficient dripless pouring spout.

Cooperating with the spout 11 to form an efficient seal for the contents of the container is a cap 16 having a top 17 and a depending contractile skirt 18. This skirt is provided with a plurality of slots 19 extending upwardly from the bottom thereof, the metal between the slots being rolled upwardly to form sleeves 20, thereby providing a discontinuous angular seat for a contractile clamping ring 21. The ends of the wire are formed into hooks 22 which are located in a wide slot from which the metal of the skirt has been rolled into a rear sleeve 23.

For the purpose of contracting the ring 21 and skirt, I provide a sheet metal lever 24 having a handle portion 25 and a head 26. This head consists of a pair of spaced ears 27 which project upwardly and at an angle to the longitudinal axis of the handle. The ears converge inwardly and forwardly of the handle and each ear is of a substantially flat circular shape and is provided with a centrally disposed aperture 28 through which one of the wire hooks 22 is adapted to project, as clearly shown in Figures 1 to 5 and 9. The handle 25 is preferably curved convexly to facilitate operation of the lever and for the purpose of strengthening the lever it is formed with a reinforcing rib 29 extending around the contour of the handle. The ears are also formed with reinforcing ribs 30 and there is a cross reinforcing rib 31 extending between the two ears.

The ears 27 comprise cams which upon a rotary movement of the lever about the apertures as a pivot, effect a contraction and expansion of the wire 21 and consequently a contraction and expansion of the cap skirt 18. It will be observed that each hook 22 before it passes through its corresponding aperture 28 is curved around the front face of the ear. This face therefore constitutes a cam surface over which the hook rides and cooperates with the other cam surface to cause the expansion and contraction of the ring and skirt.

The interior of the top of the cap is preferably provided with a liner 32 and the skirt 18 is of sufficient depth to permit the ring 21 to extend below the edge 15 of the flange 14 when the cap is first applied to the spout 11. The ring and skirt will initially be in expanded position with the lever in the dotted line position shown in Figure 5. The liner 32 will lightly contact with the sealing surface 13 throughout its entire periphery and the ring 21 will be directly below the edge 15 of the flange 14. As the lever is grasped by the fingers of the operator and moved outwardly and downwardly to the position shown in full lines, Figure 5, the ring and skirt 18 will be contracted about the flange 14. This action will effect an inwardly and downwardly pull on the cap skirt and thus provide a tight effective seal between the sealing surface 13 and the liner 32. Furthermore, by reason of the spout and the flange 14 being formed of sheet metal, the latter is subjected to the force of the contracting action of the ring 21 and will be placed under tension, thus fur-

ther increasing the sealing action between the cap and spout.

It will be apparent that the present spout and cap combination incorporates all of the advantages of the prior art constructions without their defects. That is, the spout with its pouring lip and narrow depending flange insures a dripless action and by reason of the uniform contour of the flange 18, the efficiency of the sealing action is not sacrificed, as is the case where the flange is interrupted or cut away in the pouring lip.

The flange terminates short of the lower wired edge of the closure, as best shown in Fig. 5, except at the lever where the cap skirt is curled upwardly to form the sleeve 23. By forming the spout flange relatively narrower than the cap skirt, the edge of the latter extends below the free edge of the spout flange, and upon operation of the lever is contracted slightly beneath the flange, insuring a uniform engagement of the cap skirt with the spout throughout the skirt circumference except at the sleeve 23 where the skirt is shortened so as to substantially eliminate the skirt at the lever slot. The cap is thus retained upon the spout not only by the frictional engagement of the inner skirt surface with the outer surface of the flange, but also by the contraction of the wired edge of the skirt beneath the free edge of the spout flange. The uniform width of the flange thus assures not only a continuous frictional engagement of the cap skirt with the flange, but a uniform locking of the wired edge of the cap beneath the edge of the flange circumferentially of the cap. The spacing of the flange edge from the spout wall provides a relatively yielding and sharp surface to be engaged by the cap skirt when the latter is contracted and one which is concealed within the cap when the latter and the spout are assembled.

Furthermore, the particular construction of the lever adds greatly to the efficiency of the cap. By forming the levers of sheet metal they may be made in quantity production and with great precision. This is important in that any slight variation in the relative sizes of the cams will affect the operating efficiency of the lever and cap.

In Figures 12 and 13 there are disclosed two steps in the formation of a slightly modified form of ear or cam for the lever 25. In this arrangement each ear 33 is first formed with a relatively small aperture 34 surrounded by a flat portion 35 contained within the ribbed portion 36 of the ear. The portion 35 is so formed as to permit the same to be rolled outwardly and inwardly as at 37, Figure 13. This provides a smooth rounded bearing surface for the hook 22 of the contracting wire and prevents the aperture from having any rough edges which might cut into the metal of the hook and thus shorten the life of the cap.

In Figure 8, there is disclosed a cap 38 having a contractile skirt 39 similar to that shown in Figures 1 to 5. In this view, however, the lever 40 is formed of wire instead of sheet metal and cooperates with the hooks 41 through the loops 42. This illustration is primarily to show that a cap having this type of lever is capable of providing an efficient seal between the sealing surface 13 and the cap liner 32. In other words, the novel combination of the spout and cap, as above described to produce a dripless spout and an efficient seal, is not dependent upon

the use of my sheet metal lever. It is to be understood, however, that my sheet metal lever constitutes a substantial improvement and has many advantages over the wire type of lever.

Referring now to Figures 14 to 22, there is disclosed the method of forming the spout 11. These figures illustrate the successive steps in the formation of the spout from the flat annular blank 43 shown in Figure 14. Several drawing operations are initially performed on this blank, the first operation blanking out the metal to the form shown in Figures 15 and 15a. In these views, the blank has been formed into a substantially cup shaped article 44 having a cylindrical wall 45 provided with a bottom 46, the upper extremity of the wall terminating in a flat annular flange 47. The subsequent drawing operation is for the purpose of reducing the diameter of the cylindrical portion 45 such as disclosed in Figures 16 and 16a.

The next step comprises the formation of the pouring lip 48, this lip being pressed into portions of both the cylindrical wall 45 and the flange 47, as illustrated in Figures 17 and 17a. The cup is then pierced or punched to remove the greater portion of the bottom 46 of the cup, this operation leaving a slightly inturned flange 49, as shown in Figure 18. In the next step, this flange is straightened out as at 50 in Fig. 19 to form a portion of the cylindrical wall 45 and completely eliminate any base or bottom wall to the spout.

In the next operation, as shown in Figures 20 and 20a, the flange 47 is trimmed to its final dimensions, after which it is bent or rolled to provide an interrupted depending skirt 51, as shown in Figures 21 and 21a. As clearly described in the earlier part of the specification, it is quite important that this flange bending or rolling operation produce a uniform upper sealing surface extending in substantially a single plane to permit this surface to cooperate with the contractile cap to provide an efficient seal between these two elements. It is also important that the depending skirt portion be continuous and interrupted in order that it may cooperate with the contracting flange of the cap to retain the sealing surfaces in operative relation. If desired, the spout may undergo a further operation in order to form an annular jaw bead 52 on the cylindrical portion 45.

It will be understood that the invention is not limited to the details of construction shown in the drawings and described in the specification, and that the example of the use of the device which has been given does not include all of the uses of which it is capable; also, that the phraseology employed in the specification is for the purpose of description and not of limitation.

I claim:

1. In combination, a container having a spout provided with a pouring lip and a sealing surface surrounding the pouring lip and having a substantially oval contour, said spout having a uniform, outwardly and downwardly turned depending flange forming a continuation of the sealing surface and terminating in an edge spaced outwardly from the wall of the spout, a cap having a substantially oval top engageable with the sealing surface and having a skirt adapted to extend below the edge of the spout flange, and lever means at the rear blunt end of the cap for projecting the skirt under the free edge of the spout flange at the sharp, pointed end of the lip to effect a sealing engagement

between the cap and sealing surface, particularly at the latter end.

2. A pouring spout comprising a cylindrical neck at the lower end thereof and a head at the upper end thereof, comprising a rear portion constituted by a straight line continuation of the cylindrical neck, a forwardly projecting lip portion disposed on a substantially frusto-conical surface joining the rear portion, and a substantially uniformly outwardly and downwardly turned flange extending entirely around the lip portion and the rear portion, and terminating in a free lower edge spaced outwardly from said portions, the upper end of said spout being disposed to lie in a common plane.

3. A pouring spout having an upper end adapted to be sealed by a closure having a plane, downwardly facing sealing surface, said spout comprising a substantially circular, cylindrical lower portion adapted to be secured at its lower end to a receptacle; an upper portion comprising a rear section formed from a straight upward continuation of the lower portion, and a front, lip section formed from an outwardly and upwardly projecting, inclined wall forming a pouring lip, the upper ends of both of said sections being disposed in a common, substantially horizontal plane, and an outwardly and downwardly turned marginal flange extending entirely around the upper end of the spout and constituting an integral continuation of both said rear section and said lip section and constituting a reinforcing means for the latter to maintain the upper end thereof in said common plane, said flange terminating in a free edge substantially entirely around the spout and adjacent the lip end thereof and being adapted to be engaged by the lower end of the skirt of a receptacle closure in hooked relation thereunder to maintain a tight seal between said downwardly facing sealing surface thereof and the lip end of the spout.

4. A spout comprising a substantially circular, cylindrical lower neck portion, and an upper portion having an oval margin at its upper end, and a substantially uniform outwardly and downwardly turned marginal flange, all points on the upper end of the spout being disposed to lie in a common plane, the rear blunt end of the oval being formed by a straight upward continuation of the cylindrical neck, and the forward, pointed end of the oval being formed at the upper end of an outwardly and forwardly inclined lip portion merging with the cylindrical portion, said depending flange terminating in a free edge spaced outwardly from the inclined lip portion and providing a substantially dripless pouring lip and also serving as an abutment under which the depending skirt of a closure may be projected by securing means associated therewith.

60 5. In combination, a pouring spout and a closure cap for the spout, said spout comprising a lower cylindrical neck portion adapted to be secured to a container, and a head at the upper end of the neck comprising a rear portion constituted by a straight line continuation of the cylindrical neck, a forwardly projecting lip portion disposed on a substantially frusto-conical surface, and a substantially uniform outwardly and downwardly turned flange extending entirely around the spout and terminating in a free lower edge and providing a substantially dripless pouring edge for the lip portion, said closure cap comprising a top having a downwardly facing sealing pad engageable with the upper surface of the flange entirely around the perimeter

thereof, a depending skirt having a portion projecting under the free edge of the flange at the lip portion of the spout, and lever means carried by the cap at the rear end thereof for drawing the skirt under the free edge of the flange at the lip portion to effect a tight sealing engagement between the pad and the upper surface of the flange, particularly at the lip portion thereof.

6. In combination, a pouring spout and a closure cap for the spout, said spout comprising a lower cylindrical neck portion adapted to be secured to a container, an outwardly projecting, horizontally disposed circumferential rib at the upper end of the neck, positioned to be engaged and gripped by the supporting jaws of a filling or closing machine, and a head above said rib comprising a rear portion constituted by a straight line continuation of the cylindrical neck, a forwardly projecting lip portion disposed on a substantially frusto-conical surface, and a substantially uniform outwardly and downwardly turned flange extending entirely around the spout and terminating in a free lower edge and providing a substantially dripless pouring edge for the lip portion, said closure cap comprising a top having a downwardly facing sealing pad engageable with the upper surface of the flange entirely around the perimeter thereof, a depending skirt having a portion projecting under the free edge of the flange at the lip portion of the spout, and lever means carried by the cap at the rear end thereof for drawing the skirt under the free edge of the flange at the lip portion to effect a tight sealing engagement between the pad and the upper surface of the flange, particularly at the lip portion thereof.

7. In combination, a pouring spout and a closure therefor, said spout comprising a lower cylindrical neck fixedly adapted to be secured to a container, an upper portion comprising a rear

section formed from a straight upward continuation of the neck, and a front lip section formed from an outwardly and upwardly projecting, inclined wall forming a pouring lip, and an outwardly and downwardly turned, integral marginal flange extending entirely around the upper end of the spout and constituting a reinforcing means to maintain the lip section against deflection under sealing pressure, said flange terminating in a free edge adjacent the lip end of the spout and providing a substantially dripless pouring edge, said closure cap comprising a top, a sealing pad below the top positioned to engage the upper face of the flange entirely around the perimeter of the spout, a depending skirt having a portion engageable with the edge of the flange at the lip end of the spout, and lever means carried by the opposite end of the cap for drawing the skirt downwardly to effect tight sealing engagement between the pad and the flange, particularly at the lip end.

8. A sheet metal lever for use with a container closure having a contracting ring associated with its skirt, said lever comprising a rearwardly projecting handle portion and a head having spaced substantially circular ears projecting upwardly from the plane of the handle and lying in angularly disposed, rearwardly diverging planes with respect to the longitudinal axis of the handle so that the facing surfaces and circumferential edges of the ears diverge rearwardly and converge forwardly, said ears being provided with centrally disposed apertures for receiving the rearwardly and laterally bent ends of said contracting ring, said facing surfaces and edges of said ears constituting cam surfaces around which the end portions of the contracting ring are bent, whereby, upon pivoting movement of the handle about the center of the apertures, the ends of the ring are contracted or expanded.

CARL McQUINN.
